UNITED STATES PATENT OFFICE.

RUDOLPH SKOOG, OF NEW YORK, N. Y.

WHISK-BROOM HOLDER.

SPECIFICATION forming part of Letters Patent No. 270,187, dated January 2, 1883.
Application filed July 18, 1882. (Model.)

To all whom it may concern:

Be it known that I, RUDOLPH SKOOG, of the city, county, and State of New York, have invented certain new and useful Improvements 5 in Whisk-Broom Holders, of which the following is a full, clear, and exact description.

Reference is to be had to the accompanying drawings, forming part of this specification, in which similar letters of reference indicate corresponding parts in all the figures.

Figure 1 is a perspective view of one form of my improved holder, part being broken away. Fig. 2 is a sectional plan view of a part of the same, taken through the line *x x*, Fig. 1. Fig. 15 3 is a sectional elevation of the same, taken through the line *y y*, Fig. 2. Fig. 4 is a perspective view of another form of the same, part being broken away. Fig. 5 is a sectional plan view of the same, taken through the line *z z*, Fig. 4. Fig. 6 is a sectional elevation of another form of the same.

The object of this invention is to provide receptacles for whisk brooms and brushes, which shall be constructed in such a manner that the brooms and brushes can be readily put in and taken out, and which shall be neat and ornamental in appearance.

In the forms of my improvement shown in Figs. 1, 2, 3, and 6 the frame A is made in 30 rectangular form, with double corner posts connected by side and end rounds, and the casing B, which may be pasteboard, wood, or other suitable material, is attached to the inner posts, leaving the outer posts at the outside of 35 the said casing as an ornament.

The holders or whisk-clamps are provided with springs C for supporting the broom or brush while in the holders, which may be attached to the lower end rounds of the frame A, 40 as shown in Fig. 1, to the lower side rounds, as shown in Fig. 4, or to the upper end rounds, as shown in Fig. 6.

The springs C can be made of any desired or convenient form that will receive and support 45 the shoulders of the broom or brush, and that will yield to allow the brush or broom to be withdrawn downward through the holder.

In the construction illustrated in Figs. 1, 2, and 3 the springs C are made of wire, with

coils in the wire near the points of attachment 50 to the rounds, and with metal plates attached to the wires.

In the construction illustrated in Fig. 6 the wires of the springs C are attached to the upper end round, extend downward and inward, 55 have coils formed in them at or near the lower end rounds of the frame, and are then curved outward and upward so as to rest against the inner surface of the end plates of the case B and slide up the said plates when the springs 60 are forced back by the brush while being drawn down through the holder. In this case the parts of the springs between the upper end rounds and the coils are covered with metal plates.

In the construction illustrated in Figs. 4 and 5 the frame A is made flat and with double side posts, and the casing B is formed of two plates—one flat and the other curved—to form a receptacle for the broom or brush. In this 70 case the springs C are attached to the side round of the frame, and may be made separate or connected by being made of a single piece wire.

The springs C can be made of wire covered 75 with metal plates, or of wire without the metal plates, or of metal plates without wire, the construction of the springs being immaterial so long as they are so formed as to support the broom or brush and to yield to allow the said 80 brush or broom to be drawn downward past them.

I am aware that boxes have been employed to contain spring-clamps adapted to hold a whisk yieldingly, so that it may be readily put 85 in and held or readily pulled out; but

What I claim is—

A whisk-holder formed of two frames connected by cross-rods, and having on each of the lower of these cross-rods two spiral wire 90 springs connected by an extension wire frame adapted to hold the whisk-clamps between the frames, as shown and described.

RUDOLPH SKOOG.
